UNITED STATES PATENT OFFICE.

GEORGE WALKER, OF PLANTSVILLE, CONNECTICUT, ASSIGNOR TO THE LANDERS, FRARY & CLARK, OF NEW BRITAIN, CONNECTICUT.

DESIGN FOR A FRAME FOR VEGETABLE-SLICERS.

SPECIFICATION forming part of Design No. 33,552, dated November 13, 1900.

Application filed October 16, 1900. Serial No. 33,301. Term of patent 14 years.

To all whom it may concern:

Be it known that I, GEORGE WALKER, a citizen of the United States, residing at Plantsville, in the county of Hartford and State of Connecticut, have invented and produced a new and original Design for a Frame for a Vegetable-Slicer, of which the following is a specification, reference being had to the accompanying drawings, forming part thereof.

Figure 1 is a front elevation of a frame for a vegetable-slicer, showing my new design. Fig. 2 is a plan view of the same.

As shown in the drawings, the body of the frame or hopper A is mainly circular in plan view, with a slight projection on one side of its door or cover D, bordered by a straight bead 3. In front view this hopper is of a triangular form, straight and vertical at its right-hand end 4 and mainly straight and horizontal at its upper end 5, but with an upwardly-projecting wing 6 at the upper right-hand corner, the entire upper and right-hand end being bordered by the rounded bead 7. The other side of the triangular contour of the hopper in front view is mainly on substantially a quarter-circle, of which the wing 6 is the center; but there is a semicircular projection 10 just below the bead 7 at the upper left-hand corner. The upper end of the hopper is provided with a door D of the same shape as the hopper in plan view and composed, essentially, of concentric rings 8 and radial bars 9.

The hopper A rests upon a standard having a horizontal member 11 and vertical member 12, from the right-hand edge of which vertical member the lateral wings 13 and 14 project. The junction of the vertical member 12 and its wing 14 is rounded, as shown at 15, Fig. 1, and the outer end 16 of the said wing 14 is also rounded. A second vertical member 17 projects upwardly from the right-hand end of the vertical member with a rounded corner, as shown, and at the upper end of the said second vertical member there are two circular members 18. The entire standard is mainly in the form of a flat web with a rounded bead at one edge. This bead 19 commences at the lower lateral wing 14, then extends upwardly along the right-hand edge of the vertical member 12, the lower edge of the horizontal member 11, and then crossing the web of the said member on a curve passes up on the left-hand edge of the second vertical member 17 and along the upper edge of the web between the two circular members 18, all combined in a unitary design.

Having described my invention, what I claim as new, and desire to secure by Letters Patent, is—

The design for a frame for a vegetable-slicer, as herein shown and described.

GEORGE WALKER.
